UNITED STATES PATENT OFFICE.

ALBERT HUPP, OF KANSAS CITY, MISSOURI.

AUTOMATIC MAIL-EXCHANGE SYSTEM.

1,163,928.

Specification of Letters Patent. Patented Dec. 14, 1915.

Application filed April 17, 1912. Serial No. 691,497.

To all whom it may concern:

Be it known that I, ALBERT HUPP, a citizen of the United States, residing at Kansas City, in the county of Jackson and State 5 of Missouri, have invented certain new and useful Improvements in Automatic Mail-Exchange Systems, of which the following is a specification.

This invention relates to mail exchange 10 systems of that type which automatically effect an exchange of mail between stations along the line of railroad and the trains traveling over such road, and has for its object to produce an efficient, reliable and 15 comparatively simple apparatus of such character that the mechanism carried by the train may operate in conjunction with or independently of the station apparatus at either side of the trackway irrespective 20 of the direction in which the train is moving.

A further object is to provide a normally 25 locked cam wheel on a mail car, to be unlocked and thrown by a trip near the roadway, into gear with an axle of the car, and mechanism 30 operated by said cam wheel, for opening and closing one or all of the side doors of the car; setting a catcher arm to take one or more mail sacks from a station crane or 35 cranes and discharge such sack or sacks into the car through an open doorway and returning such arm to normal position; causing 40 one or more baskets to move through a doorway or doorways and discharge sacks 45 of mail destined for a station and for returning such basket or baskets to normal 50 position before the door or doors are closed.

Another object is to provide means to be 55 thrown into gear with the car axle by the action of the trip, and adapted for adjustment manually into or out of gear with the cam wheel to cause the same to operate with the axle in a forward direction to operate the doors, catcher arm and a basket and in 60 a reverse or backward direction to effect the premature return of the door or doors, catcher arm and basket or baskets to normal position, means for automatically 65 throwing the cam wheel out of gear with the axle and means for locking it in such condition until again thrown into gear with the axle through the instrumentality of a 70 trip near the trackway.

Another object is to produce a cam wheel 75 capable of adjustment to accommodate car

wheels of different diameter or to compensate for wear.

Another object is to provide manually 80 controlled means for throwing a door and a basket out of gear with the actuating mechanism.

Another object is to provide manually 85 controlled means for each basket to prevent the same from moving to delivering position.

Another object is to provide manually 90 controlled means for preventing the setting of the catcher arm or for effecting the return of the same to normal position either before or after it attains its operative position to receive mail from the station.

Another object is to provide means 95 whereby either or both of the baskets may be caused to operate in conjunction with either set of side door openings, and means 100 whereby the catcher arm at either side, may be reversed or changed to the opposite side of the door to avoid the necessity of turning the car around for the return trip thereof after reaching a terminal.

Another object is to produce means 105 whereby the connections between the cam wheel, the doors, the catcher arm and the basket-operating mechanism is locked against automatic movement unless the cam 110 wheel is first unlocked and thrown into gear with the driving axle.

With these general objects in view and others as hereinafter appear, the invention 115 consists in certain novel and peculiar features of construction and organization as hereinafter described and claimed; and in order that it may be fully understood reference is to be had to the accompanying drawings, in which:

Figures 1, 2 and 3 conjointly represent a 120 side elevation of part of a mail car, equipped with apparatus embodying my invention, Fig. 3, also illustrating a rail clearing device and a trip for throwing the car apparatus in operation. Figs. 4 and 5, represent horizontal sections respectively, of Figs. 1 and 2, taken through the upper portions of the door openings, the bottom of the car being broken away to expose mechanism below the same. Fig. 6, is an enlarged vertical transverse section taken approximately on the line VI—VI of Fig. 3. Fig. 7, is a vertical section of a station trip on line VII—VII of Fig. 8. Fig. 8, is a 125

section on the line VIII—VIII of Fig. 7. Fig. 9, is a plan view of the trip and of part of the adjacent track rail. Fig. 10, is a horizontal section on the line X—X of Fig. 6. Fig. 11, is a vertical section on the line XI—XI of Fig. 3. Fig. 12, is an enlarged vertical longitudinal section of power transmitting mechanism embodying my invention. Fig. 13, is a plan view of part of the mechanism shown by Fig. 12. Fig. 14, is a plan view of all of the mechanism shown by Fig. 12, except the casing for such mechanism, certain parts of said figure being broken away. Fig. 15, is a view taken on the line XV—XV of Fig. 13, but on a larger scale than the latter. Fig. 16, is a transverse section on the same scale as Fig. 15, on the line XVI—XVI of Fig. 12. Fig. 17, is a transverse section on the line XVII—XVII of Fig. 12. Fig. 18, is a plan view of a cam wheel shown in section in Fig. 12 and partially shown in Fig. 14. Fig. 19, is a section on the line XIX of Fig. 12, and shows part of a ring carried by the cam wheel, means for locking the same against rotation and means to trip the locking device from engagement with the ring. Fig. 20, is a detail perspective view of the pivoted catch partially shown in Fig. 19. Fig. 21, is a detail perspective view of the ring rotatable with the cam wheel. Fig. 22, is a cross section on the line XXII—XXII of Fig. 5, and showing above the floor line of the car, the doors in closed position and the door operating mechanism, the trackway and the traveling basket mounted thereon. Fig. 23, is an enlarged section on the line XXIII—XXIII of Fig. 22. Fig. 24, is a section on the line XXIV—XXIV of Fig. 23. Fig. 25, is a section on line XXV—XXV of Fig. 23 with the basket in the position it assumes between its initial position within the car and its dumping position through the doorway. Fig. 26, is a view showing the same mechanism as in Fig. 25, but with the basket advanced to dumping position. Fig. 27, is a plan view of the trackway extending transversely of and secured to the bottom of the car. Fig. 28, is a plan view of a pair of trucks which normally abut at their inner ends and are each adapted for travel toward and from the doorway nearest thereto. Fig. 29, is a side view of the abutting trucks. Fig. 30, is an enlarged section on the line XXX—XXX of Fig. 28. Fig. 31, is an inverted plan view of the basket. Fig. 32, is an enlarged section on the line XXXII—XXXII of Fig. 22. Fig. 33, is an enlarged section on the line XXXIII—XXXIII of Fig. 24 but shows only a pair of slotted parallel flanges forming part of the basket and a block adapted for location at one end or the other of the slots of said flanges accordingly as the basket is to operate in one or the other of a pair of opposite doorways. Fig. 34, is a detail perspective view of the adjustable block shown in Fig. 33. Fig. 35, is an enlarged horizontal section of the mail bag catcher appliance in its open or operative position on the line XXXV—XXXV of Fig. 2. Fig. 36, is a horizontal section on the line XXXVI—XXXVI of Fig. 2 on a larger scale than Fig. 35, the appliance being shown in inoperative position. Fig. 37, is an enlarged section on the line XXXVII of Fig. 5. Fig. 38, is a horizontal section on the line XXXVIII—XXXVIII of Fig. 37. Fig. 39, is a section on the line XXXIX of Fig. 4. Fig. 40, is a section on the line XL—XL of Fig. 39. Fig. 41, is a plan view of one of the slotted extension plates shown in section in Fig. 39. Fig. 42, is a vertical section to disclose one of the slide doors and mechanism carried by and connected with said door. Fig. 43, is an enlarged vertical section on the dotted line XLIII of Fig. 42. Fig. 44, is a section on the line XLIV of Fig. 42 and also shows a key for unlocking the door manually. Fig. 45, is an enlarged vertical section taken through the door shown in Fig. 2 to disclose part of the mechanism for preventing or effecting operation of the gathering arm. Fig. 46, is a horizontal section on the line XLVI of Fig. 45. Fig. 47, is a section on the line XLVII—XLVII of Fig. 46 but on a larger scale. Fig. 48, is an enlarged perspective view of a portion of the mechanism operated through the instrumentality of the cam wheel. Fig. 49, is a plan view of the right handed end of said mechanism on the scale of Fig. 14 but with certain parts in the positions they occupy after the trip has thrown the apparatus in gear. Fig. 50, is an enlarged longitudinal section of a shock absorber shown in Fig. 12. Fig. 51, is a detail perspective view of one of a set of slide bars shown in Fig. 48. Fig. 52, is a detail view of the hanger member of the crane for supporting the catcher arm while the same is being turned to accommodate reverse travel of the car.

In the said drawings, 1 indicates a mail car, 2 one of the axles thereof, 3 a worm on said axle, and 4 an intermeshing worm wheel, said worm and wheel being arranged within a casing 5, which has a longitudinal extension supported by a hanger 6 depending from the car, and journaled in said casing and rigidly carrying wheel 4, at one end is a longitudinally extending tumbling shaft, consisting preferably of three sections 7 universally connected at 8, the other end being journaled in a frame 9, suitably supported rigidly below the car. This tumbling shaft is to accommodate the turning of the car trucks on sharp curves and the various movements of the axle and car body incident to travel. In the vertical plane of shaft 7, the

frame 9 is provided with bearings 10, (see Figs. 12 and 13) and journaled in one of said bearings is a tubular shaft 11 equipped at one end with a bevel pinion 12 and at the other with a clutch member 13. Journaled in the other bearing 10 is a tubular shaft 14, equipped at one end with a bevel pinion 15 and at the other end with a clutch member 16, and journaled in said tubular shafts and aligned with and adjacent to the tumbling shaft, is a shaft 17, upon which is keyed a sleeve 18, terminating at one end in a clutch member 19 for engagement with clutch member 13, and at the other end in a clutch member 20, for engagement with clutch member 16. The sleeve 18 is peripherally grooved, and journaled on the grooved portion thereof is a collar 21, adapted through the instrumentality of mechanism herein-after described, to impart longitudinal movement to the sleeve for the purpose of causing clutch member 19 to engage clutch member 13, or clutch member 20 to engage clutch member 16, the range of movement of the sleeve being sufficient to permit both of these clutch members to stand disengaged from the adjacent or companion clutch members, it being understood, however, that under normal running conditions clutch member 19 will be engaged with clutch member 13 or clutch member 20 will be engaged with clutch member 16, accordingly as the car is traveling in one direction or the other.

22 is a cross bar connecting the sides of frame 9, and secured in and projecting vertically upward from said cross bar is a stub shaft 23, the upper portion of said shaft extending through a spacing collar 24, and journaled on said stub shaft between cross bar 22 and collar 24 is a cam wheel 26, provided with a bevel gear 27 meshing with bevel-pinions 12 and 15. This cam wheel is provided with an inner or door-operating cam groove 28, (see Figs. 14 and 18) an intermediate or catcher arm operating cam groove 29, and an outer or truck operating cam groove 30. Cam groove 28 consists of portions 31 and 32 concentric with the shaft 23 and of relatively large and small radius and length respectively, a door-opening portion 33 connecting adjacent ends of portions 31 and 32, and a door-closing portion 34 connecting the other ends of said portions 31 and 32. The catcher arm operating groove 29 consists of portions 35 and 36, concentric with shaft 23 and of large and small radius and length respectively, a catcher arm opening portion 37 connecting adjacent ends of portions 35 and 36, and a catcher arm closing portion 38 connecting the other ends of portions 35 and 36.

The truck operating cam groove consists of a portion 39 struck from the center of the shaft 23 and covering a range of approximately two hundred and seventy degrees,

an inwardly-bowed portion 40 diametrically opposite the center of portion 39, an eccentric portion 41, connecting adjacent ends of portions 39 and 40 and adapted for effecting the outward movement of the truck herein-after described, and an eccentric portion 42 connecting the other ends of portions 39 and 40, and adapted for effecting the inward or withdrawing movement of the truck. The wheel 26 is also peripherally recessed at 43, to provide cam or inclined shoulders 44 and 45.

Arranged around gear wheel 27 and carried by the cam wheel, is a ring 46, (see Fig. 21) provided with a triangular-shaped opening 47, and a depending annular flange 48 having an outwardly tapering opening 49, and said ring is also provided at diametrically opposite points, with a pair of upwardly-projecting lugs 50 (one only appearing, see Fig. 14) to which is pivoted the opposite ends of an arcuate catch 51 provided with a tooth 52 depending through the opening 47 of the ring and disposed in longitudinal alignment with the flange opening 49, and said catch 51 is provided with an extension or lip 53, projecting beyond the periphery of the ring, as shown in Fig. 12.

54 is a pin which is slidably arranged in one end wall of frame 9 and in an upwardly-projecting lug 55 of said frame, this pin being provided at its outer end with a cross head 56, the inner end of the pin normally engaging the recess 43 of the cam wheel 26 so as to be forced outwardly by the shoulder 44 as said cam wheel revolves in the direction indicated by the arrow, Fig. 14. The shoulder 45 of the cam wheel permits said pin 54 to be moved inward, for a purpose which hereinafter appears, just before the revolution of the cam wheel is completed. In the event the car is backed after the said pin has been permitted to be reprojected into recess 43 and the motion of the cam wheel is therefore reversed, shoulder 45 will force said pin outwardly, and if the back revolution of the wheel is sufficient, shoulder 44 may pass the pin and thus permit the same to be reprojected into the recess 43, it being understood in this connection that these eventualities may develop where necessity arises for backing the car after the exchange mechanism has been set in operation and before the wheel has completed its revolution and has been relocked in a manner and by means hereinafter described.

57 is a pair of vertical rock-shafts journaled in laterally-projecting portions 58 and 59 of the frame 9, and provided at their upper ends with crank arms 60 engaging the outer side of cross-head 56 of slideable pin 54, and said shafts are further provided, at their lower ends, with crank arms 61 extending toward the center of the car and substantially at right angles to arms 60, retrac-

tile springs 62 connecting arms 60 with the frame 9 for the purpose of holding the arms 61 yieldingly against levers hereinafter described, so that either of said arms shall be ready to interlock with the proper lever 5 automatically operated for the purpose of throwing the cam wheel in gear with the tumbling shaft, the tensioned spring 62 being adapted, as the shoulder 45 clears the 10 end of pin 54 after the cam has nearly completed its revolution, to reproject said pin into recess 43 and incidentally effect the release of said lever so that the same may be returned to its original position and be 15 ready to repeat its original operation.

In the horizontal plane and at opposite sides of shaft 17, is a pair of guide rods 63, (see Figs. 13, 15 and 17) which project beyond one end of frame 9 and are equipped 20 with rigid collars 64, against which bear coiled springs 65, fitting slidably on the tubular arms 66 of a pair of arcuate bars 67 (see Fig. 16) which terminate at their inner or adjacent ends in a pair of trip arms 68 25 (see Figs. 12, 13 and 15) arranged side by side and extending parallel with and above shaft 7, said arms being stepped upwardly at their inner ends at 69, to avoid conflict with a part hereinafter described, and the 30 upper portions of said arms underlie the lip 53 and are provided with upwardly-projecting beveled lugs 70, either of which is adapted under certain conditions, to swing the pivoted arcuate catch 51 out of the path of 35 movement of an arched disengaging yoke 71 provided with longitudinally arranged arched arms 72, slidably mounted upon the rods 63, and surrounding said rods and bearing at their rear ends against the rear 40 portions of said arms, are coiled springs 73, which bear at their front ends against collars 74 secured to rods 63 (see Fig. 15.)

Secured on one end of shaft 17 and adapted to receive the adjacent end of shaft 7, is 45 a crown gear or clutch member 75, and keyed to slide on shaft 7 is a sleeve 76, (see Figs. 12, 13 and 50,) provided at one end with a circumferential flange 77. Journaled on said sleeve is a hub 78 which abuts at one end 50 against said circumferential flange and is provided at its opposite end with a crown gear or clutch member 79 adapted under certain conditions to engage the gear or clutch member 75 as hereinafter explained, 55 and said hub is provided with a circumferential groove 80 and a circumferential flange 81. Secured around flanges 77 and 81, is a shell 82, and surrounding the hub within the shell and secured at its opposite ends to the 60 flanges of the hub and sleeve is a coiled torsional spring 83. The function of this spring is to cushion the shock incident to the engagement of the constantly driven gear 79 with the gear 75, the arrangement being such that the spring will yield slightly 65

in overcoming the inertia of the cam wheel through the direct connection of the same with the shaft 17 and will recover after the cam has completed its revolution and the gear 79 has been withdrawn from engagement with the gear 75.

84 is what I term an engaging yoke, the same fitting in the groove of the hub 78 and terminating in parallel arms 85 secured rigidly to rods 63, (see Fig. 15) and said engaging yoke is provided centrally with an upwardly-projecting tooth 86 normally engaging the opening 49 of the flange of the ring 46, for the purpose of preventing rotatable movement of the cam wheel. For 80 transmitting motion from the cam wheel to a series of levers whereby doors, catcher arm and trucks are operated, the following mechanism is provided: 87, 88 and 89 are slide bars arranged longitudinally of the 85 car and resting upon the end walls of frame 9, bar 88 having a longitudinal slot 90 to receive and avoid interference by stub shaft 23, and secured to the end walls of the frame 9 above said slide bars, is the top of a casing 91, inclosing the cam wheel and adjacent parts, and held in position by a nut 92 engaging the upper end of said stub shaft. Bar 87 is provided at its underside with a laterally-projecting arm 93 equipped with a depending pin 94 engaging the door-operating groove of the cam wheel. The central bar 88 is provided with a depending pin 95 engaging the catcher arm groove of the cam wheel, and bar 89 is provided at its underside with a laterally-projecting arm 96, provided with a pin 97 engaging the truck operating groove of the cam wheel, the arrangement being such that the rotation of the cam wheel shall, through the instrumentality of 105 said pins, effect reciprocatory movement of said bars 87, 88 and 89, and said bars are provided near their ends, with longitudinal slots 98, 99 and 100 respectively, and each set of said slots at corresponding ends and 110 sides are provided with offsetting notches 101, 102 and 103. (See Fig. 51.)

104 and 105 are keepers secured upon the end walls of frame 9, (see Figs. 14 and 48) and projecting longitudinally from keeper 115 104, is a pair of arms 106, terminating in guides 107 slidably receiving a transversely-extending bar 108, provided with notches 109 in its underside receiving longitudinally extending forks 110, 111 and 112, equipped 120 with vertical pins 113 engaging slots 98, 99 and 100 at the adjacent ends of the bars 87, 88 and 89 respectively, and adapted at times to engage the offsetting notches 101, 102 and 103 of said slots. The upper tines of the 125 forks 110, 111 and 112 are provided with laterally-projecting lugs 114, adapted to be interlocked with oppositely projecting lugs 115, of keeper 104, when pins 113 occupy slots 98, 99 and 100, these interlocking lugs 130

serving to guard against accidental operation of the pair of doors at one side of the car, a catcher arm at such side, and a pair of trucks to move toward and from the doorways or openings controlled by such doors. The keeper 105 is provided with a pair of arms 116 and an arm 117, projecting longitudinally in the opposite direction from arms 106, and said arms 116 terminate in guides 118, wherein fits slidably a transverse notched bar 119, corresponding in all respects to bar 108, receiving in its notches longitudinally-extending forks 120, 121 and 122, provided with pins 123 (see Fig. 12) engaging the longitudinal slots 98, 99 and 100 at the adjacent end of bars 87, 88 and 89 respectively, the forks corresponding in construction and arrangement to forks 110, 111 and 112. The forks 110, 111 and 112 are provided with extensions 124, 125 and 126, respectively (see Fig. 4), and the forks 120, 121 and 122 are provided with like extensions 127, 128 and 129, respectively. (See Fig. 5.) The extensions 124, 126, 127 and 129 are each equipped with a longitudinally slotted plate 130, the slots having offsetting portions. (See Fig. 41.) The extensions 125 and 128 carry plain plates 131. The functions of these plates is hereinafter explained and the extensions of the forks are to permit the latter to have a slight lateral movement without affecting the connections of the said plates with certain levers hereinafter described. For throwing the forks into or out of gear with the slide bars 87, 88 and 89, and for throwing shaft 17 into gear with the tumbling shaft, the following construction is provided: 132 is a link (see Figs. 4 and 14) pivotally connecting one end of slide bar 108 with a bell crank lever 133 fulcrumed on a hanger 134 depending from the car and the opposite end of said lever is connected by a link 135 with the outer end of a lever 136 (see Figs. 1, 5 and 13) fulcrumed on a hanger 137 on the car, and pivoted also to said lever is a rod 138 attached at its opposite end to the upwardly-projecting arm 139 (see Figs. 3, 6 and 10) of a sleeve 140 journaled on a shaft 141, and said sleeve and shaft are journaled at their outer ends on a wheel truck of the car and carried by and constituting cranks of said sleeve and shaft are inverted V-shaped trip plates 142 in the vertical plane of the station trips, hereinafter described, secured adjacent to the trackway near the stations where mail is regularly or occasionally delivered, received or exchanged. The operation of sleeve 140 through movement imparted to either of the trip plates 142 by a station trip, moves bar 108 endwise (see Fig. 48) and thereby simultaneously withdraws the lugs 114 from engagement with lugs 115, and effects the engagement of pins 113 with the offsetting notches 101, 102

and 103 of the adjacent slots in the slide bars 87, 88, and 89, so that longitudinal movement of said slide bars shall impart similar movement to the said forks. Coincidentally with the operation of bar 108 for the purpose explained, lever 136 is operated to effect transmission of power from the axle 2 to the cam wheel, and to accomplish this, said lever terminates in a foot 143, (see Fig. 13) bearing against one of the arcuate bars 75 67, and said foot has a heel 144, adapted for engagement, after the lever is operated as described, by the crank arm 61, of the adjacent rock shaft 57, through the operation of the shaft by spring 62 connected thereto, this action locking the lever 136 temporarily in its new position to guard against premature return to its original position. The operation of said lever as described effects compression of the opposing spring 65 and incidentally causes the companion trip arm 68 (see Fig. 12) through its cam lug 70, to raise the pivoted catch 51 until its tooth 52 is withdrawn from the path of disengaging yoke 71 to permit springs 73 (Fig. 15) to withdraw said yoke. As this occurs, the tensioned spring 65 imparts endwise movement to the companion rod 63 and hence to the engaging yoke to move the lug 86 thereof inwardly of the ring 46 from the opening 49 thereof and thus unlock the cam wheel and cause the gear 79 to engage the gear 75 and thus start the rotation of the cam wheel in the direction of the arrow, Fig. 14, it being noted in this connection, that when the rod 63 is moved by the spring 65, the spring and disengaging yoke 71 move with it. Shortly after the movement of the cam wheel begins, shoulder 44 thereof engages pin 54 and forces the same outward and through head 56 and crank arm 60, trips arm 61 from heel 144 to permit the trip arm to be return to normal position by spring 65, and lever 136 to be returned to normal position under gravitation action by trip plate 142, and before the revolution of the cam wheel is completed, the pin 54 is returned to its original position in recess 43 of the cam wheel, under the retractive force of spring 62. When the cam wheel has nearly completed its revolution, one of the inclined faces of lug 52 of the pivoted catch 51 which of course dropped down after the cam wheel had rotated sufficiently to carry the said lug beyond the disengaging yoke 71, engages the disengaging yoke and returns it to normal position and incidentally retensions springs 73, as at this time lug 86 of the engaging yoke is engaging the inner side of flange 48 of ring 46, said lug 86 snapping back in opening 49 of said flange as the revolution of the wheel is completed, under the endwise movement imparted to rods 63 by springs 73, this reengagement of lug 86, of the en- 130

gaging yoke with the opening 49 of the ring, locking the cam wheel against further movement, as such locking action is synchronous in point of time with the disengagement of the constantly driven gear 79, from gear 75.

145 and 146 are levers (see Figs. 1 and 4) provided at their inner ends with pins 147 and 148, pin 147 normally engaging the offset of the slot of plate 130, secured to extension or shank 124 of fork 110. Pin 148 engages the plate 131 secured to said extension. Lever 145 is pivoted to a hanger 149 slidably mounted on a pair of rods 150 carried by a pair of hangers 151 depending from the floor of the car, as shown most clearly in Fig. 39.

152 is a link pivotally connecting hanger 149 with a crank 153 on the lower end of a vertical rock shaft 154 extending through the floor of the car and suitably journaled, and said rock shaft is equipped with a handle 155, within and near the floor of the car whereby it may be turned to adjust the hanger transversely and impart endwise adjustment to lever 145 for the purpose of withdrawing pin 147 from said offset and into the slot of its plate 130, and for incidentally locking said lever against an accidental movement by disposing its attenuated outer end 156 in a channeled hanger 157 depending from the car. (See Figs. 1 and 4.) Lever 146 is fulcrumed on a hanger 158, depending from the car and is adapted to be operated each time fork 110 is moved endwise. The levers 145 and 146 are pivotally connected at their outer ends by links 159 and 160, to suitably guided longitudinally-extending rack-bars 161 (Fig. 4) and 40 162 (Fig. 5) respectively, said rack-bars being disposed below the car floor. The said rack-bars respectively engage cog gears 163 and 164 mounted on the lower ends of vertical shafts 165 and 166 extending upward into the car and suitably journaled in bearings 167 secured to the adjacent side of the car. (See Fig. 42.)

As the four doors of the car hereinafter described and the mechanism for directly operating them from shafts 165 and 166 and for locking them to or unlocking them from such mechanism, is identical, it is shown only in Figs. 42 to 44 inclusive. Referring now to Fig. 42, 168 is a pair of gear pinions 50 shown as mounted on shaft 166 and meshing with a pair of longitudinally-extending suitably-guided rack-bars 169, fitting in alined channel bars 170 secured to the inner side of door 171, and to retain the rack-bars in the channel bars 170 as regards lateral movement, the latter are provided with suitably-spaced keepers 172. The door is suspended by hangers 173 from an overhead track bar 174, secured within the car.

To secure the rack-bars and channel bars 65 rigidly together so that movement of the former shall impart travel to the door, the rack-bars are provided with sockets 175 (see Fig. 43) normally engaged by the vertical arms of catches 176 pivoted to the channel bars and extending slidably up through the adjacent keepers 172 and the channel bars, and said catches are provided with crank arms 177 pivotally connected by links 178 to crank arms 179 of a rotatable door knob 75 or handle 180, a retractile spring 181 tending to hold the catches interlocked with the rack-bars, as shown most clearly in Figs. 42 and 43.

From the foregoing it will be seen that 80 longitudinal movement of the fork 110 invariably rocks lever 146 and also rocks lever 145 if the pin 147 of the same is in engagement with the offset notch of its slotted plate 130, and that the operation of said 85 levers in one direction through the mechanism described, effects the simultaneous opening of the two doors at the same side of the car, reverse movement of said fork effecting closing movement of the doors, 90 these opening and closing movements occurring with one revolution of the cam wheel.

To enable a mail clerk to open a door from the outside of the car, the knob is provided in its outer end with a socket 182 having 95 diametrically-opposite inwardly-projecting lugs 183 for engagement by a key 184, by means of which the clerk may turn the knob in opposition to spring 181 and withdraw the catches from engagement with the rack-bars and then slide the door open, the channel bars in this action telescoping on the rack-bars which remain immovable. When the door is again closed the spring 181 automatically effects the reengagement of the 105 catches with the sockets in the rack-bars, as will be readily understood.

The extension or shank 127 of fork 120, is connected to the doors at the opposite side of the car by mechanism identical with that 110 described in connection with the first-named pair of doors and such mechanism is therefore identified by corresponding reference characters, but it is to be understood that such duplicate mechanism need not, and in 115 practice will not, be operated at the same time though it is possible for simultaneous action to occur if two station trips are arranged in transverse alinement, which of course would never occur in practice. It 120 will be necessary however, on single track roads to operate the duplicate mechanisms at opposite sides of the car as all of the stations are not usually on the same side of the road, and because of this it is necessary 125 to provide means for interlocking the forks 120, 121 and 122, with slide bar 87, 88 and 89, and to accomplish, this, I employ the

notched slide-bar 119 hereinbefore described, and corresponding in all respects to slide bar 108, it being noted by reference to Fig. 49, that the pins 123 of forks 120 to 5 122 inclusive may be caused to engage the offset notches 102 of the adjacent slots 98 to 100 inclusive, though said pins normally stand in the slots so that the fork 121 shall bear against the stop arm 117 of keeper 105, 10 and thus be prevented from moving longitudinally when bars 87, 88 and 89 are moved for the purpose of operating forks 110 to 112 inclusive.

For the purpose of causing bars 87 to 89 15 inclusive, to position forks 120 to 122 inclusive, with their pins in the off-sets of the adjacent slots 98 to 100 inclusive, when forks 110 to 112 inclusive, are to remain inoperative and therefore have their lugs 20 114 interlocked with lugs 115 of keeper 104, the slide-bar 119 is connected by a link 185 to a suitably-supported bell-crank 186, pivoted at its opposite end to a rod 187 connected at one end to an upwardly-projecting arm 25 188, of shaft 141 (see Fig. 6), so that the operation by a station trip, of the V-shaped plate 142 forming a crank arm of shaft 141, will move rod 187 endwise in the direction indicated by the adjacent arrow, Fig. 5, and 30 thus move the forks 120, 121 and 122 laterally to interlock them with bars 87, 88 and 89. Rod 187 is also pivotally connected to the outer end of a lever 189, corresponding in all respects to lever 136, so that the said 35 lever 189 (see Fig. 13) shall perform identically the same function as that described in connection with lever 136, lever 189 operating on the other trip arm 68. A detailed description of the operation of lever 189 40 and parts which coöperate with it, is therefore omitted.

Secured to the car, adjacent to the rear side of the rear set of opposite doorways with respect to the direction in which the 45 car is moving, are two upwardly disposed hooks 190 and a third downwardly disposed hook 191, and fitting flatly against the side of the car, is a triangular plate 192 terminating at its apex in a tongue 193 engaging 50 under the downwardly-disposed hook 191, and provided near its base with a pair of openings 194, the upper opening of the pair receiving and being overlapped by the upper upwardly-disposed hook 190, and the 55 lower edge of the plate fitting within and being overlapped by the lower upwardly-disposed hook 190, the arrangement being such that the plate is held firmly against the side of the car but may be readily raised 60 for disengagement from said hooks, and in this connection it is desired to state that the plate is provided with the two openings 194 so that when it is arranged at the opposite side of the door to accommodate re-

verse travel of the car, it may be readily engaged with a similar set of hooks 190 and 191 at such opposite side of the door, as indicated in Fig. 2.

The plate 192 is provided with a plurality of horizontal ribs 195, and extending through said ribs and journaled in bearings 196 of the plate, is a short vertical shaft 197, rigidly secured at its lower end as regards rotatable movement, to the upper end of an aligned vertical shaft 198 suitably journaled at the side of the car, and provided with a crank-arm 199 extending under the car and connected by a link 200 to one arm of a bell-crank lever 201, pivoted on a hanger 202 depending from the car. (See Figs. 2, 5 and 22.) The opposite end of the bell-crank is pivotally connected by a rod 203 to a crank-arm 204 extending under the car from the lower end of a vertical shaft 205 (Figs. 2, 5 and 45) corresponding to but located at the opposite side of the doorway from shaft 198, the arrangement being such that said shafts shall operate in unison but in opposite directions, for a purpose which hereinafter appears, and 90 said shafts 198 and 205 are prevented from sliding downward, by their respective collars 206 and 207 resting on the undermost bearings of such shafts, as shown clearly in Fig. 2. The inner end of crank-arm 204 is 95 secured in a stirrup 208 (Figs. 4, 5, 46 and 47) at one end of an arcuate plate 209, and pivoted on shaft 205 is an inwardly-projecting arm 210 which fits in said stirrup above arm 204 and is connected at its inner 100 end to a rod 211 (Fig. 5) which is connected at its opposite end to a lever 212, (Fig. 4) pivoted on a hanger 213 depending from the car, and said lever is connected to extension or shank 125 of fork 111, by the 105 plate 131 of such extension. Pivoted arm 210 extends through a vertically-slotted block 215 secured to and depending from the inner end of an arm 216 pivoted on a vertical shaft 217, extending up into the 110 car; said shaft being arranged to turn and slide in bearings 218 and 219, and secured to the lower end of shaft 217 and supporting the pivoted arm 216, is a crank arm 220, provided with a laterally-projecting 115 arm 221, for a purpose which hereinafter appears. Pivoted to the upper end of said shaft 217 and projecting inwardly of the car in a plane above the door opening, as shown in Fig. 45, is a lever 222, provided 120 with a suitably-guided spring-actuated catch 223, normally in engagement with a notched sector 224, carried by and movable with shaft 217, and said catch is connected by a link 225 with a grip-lever 226 carried by lever 222, so that by grasping said levers and pressing them relatively together, the 125 catch will be withdrawn from engagement

with the sector. When it is unlocked from the sector the handle end of the lever can be depressed and the shaft 217 raised, the lever being fulcrumed to effect this object, 5 in a slotted arm 227, arranged horizontally and rigid with bearing 219, the slotted fulcrum arm 227 being arcuate in form in order that it may constitute a fulcrum for the lever when the same is extending trans- 10 versely of the car or is occupying any position between the position named and the arrow head shown in Fig. 46, it being noted that the upper and lower sides of the slotted arm 227 are disposed at an angle to each 15 other so as to accommodate vertical movement of the lever as the latter fulcrums on the inner edge of the lower side of said arm. Under the movement first imparted to slide bar 88 by the cam wheel and transmitted 20 thence to fork 111, lever 212 is first operated to move rod 211 in the direction indicated by the arrow, Fig. 4, and the rod through its connection with pivoted arm 210, through the stirrup 208, imparts like move- 25 ment to the crank 204 and its shaft 205, and through the slotted block 215 to the pivoted arm 216; crank arm 220, shaft 217 and lever 222 being unaffected. The operation of crank-arm 204 imparts endwise movement 30 to link 203 and hence through bell crank 201, link 200 and crank 199, to the vertical shaft 198, for a purpose which hereinafter appears. If it is desired to prevent the operation of shafts 198 and 205, lever 222 is 35 manipulated to slide shaft 217 upward and by this action crank arm 220 lifts arm 216 pivoted to said shaft, and block 215 moves arm 210 vertically upward until withdrawn from the stirrup 208, and hence unlocked 40 from crank arm 204. While elevated arm 210 swings inoperatively in a substantially horizontal plane above the arcuate arm 209 rigid with crank arm 204, and through block 215 imparts like inoperative pivotal movement to arm 216, pivoted on rock shaft 217, which therefore remains inoperative as 45 regards turning movement.

Should it be desired to operate shaft 197 manually to close the catcher arm, herein- 50 after described, after the same has been opened automatically, as where no mail is to be received from a station, lever 222 after swinging automatically in the direction indicated by the arrow, Fig. 46, is grasped 55 and swung back to its original position. In this operation crank arm 220 of shaft 217, bears against the high side of the stirrup (see Fig. 47) and thus rocks crank arm 204 and shaft 197 back to normal position and 60 incidentally, through the stirrup, returns pivoted arm 210 to its original position.

From the foregoing it will be seen that through the instrumentality of lever 222 and its connections, shafts 196 and 205 can be 65 thrown out of gear with the slide bar 88, and

that, through the instrumentality of said lever, it is possible also to rerock said shafts to normal position after being automatically rotated.

The mechanism identified by parts 192 to 70 227 is duplicated at the opposite side of the car, but the duplicate lever 212 is connected to the fork 121 at the opposite end of slide bar 88, as shown in Fig. 5, it being understood that normally the pins of one set of 75 forks are in the offsetting portions of their respective slotted plates, so that the duplicate mechanisms shall not operate in unison.

The catcher arms 228 each consists of a central channel bar 229, and a channel bar 80 230, above and a similar bar 231 below bar 229, said bars being connected at one end by an end piece 232. The opposite ends of the bars are bowed slightly and terminate in extensions 233, extending at an angle to the 85 body portions and pivotally engaging shaft 198 and receiving the ribs 195 of plate 192 so as to be incapable of vertical movement on the shaft. The bars 229 and 230 are slotted for a suitable distance from shaft 90 197 by cutting out the bridge portion thereof, as shown at 234, (Fig. 36) and said slotted portions are bridged by vertical pivot pins 235. 236 are auxiliary channel arms fitting in the slots of bars 229 and 230 and 95 pivoted on said pins 235, and bifurcated at 237 at their pivoted ends, and extending into said bifurcations and pivoted at 238 to the heel ends of said arms, are links 239, pivoted at their opposite ends to the bridge portion 100 of a horizontally arranged U-shaped frame 240. The arms of said frame terminate in forks 241 receiving the slotted ribs 242 of a plate 243 fitting flatly against the outer side of the car at the opposite side of the doorway from plate 192, and said plate 243 like plate 192, is adapted for use at either side of the car door if desired. For this purpose it is provided near its lower and upper 105 ends with openings 244, the upper set of openings being adapted to fit over and be overlapped by brackets 245 projecting from the car, similar brackets 246 receiving and overlapping the lower end of the plate as shown clearly in Fig. 2. Similar brackets 115 are disposed at the opposite side of the doorway, as shown in Fig. 2. The links 239 and frame 240 constitute a toggle connection between the auxiliary arms 236 and the side of the car, for limiting outward or opening 120 movement of the catcher arm. The said frame member of the toggle is provided with arms 247 projecting into the channels of bars 229 and 230 and pivotally connected thereto at 248, and to act as stops for the 125 auxiliary arms 236 when in operative position as shown in Fig. 35, and incidentally coöperate in limiting the opening movement of the catcher arms, the ribs 195 are provided with arms 249 which project into the 130

doorway. When the catcher arms are in their closed positions, as shown in Fig. 36, the major portions of their bars fit flatly against the outer side of the car and their bowed portions extend slightly into the door openings, and the auxiliary arms occupy the positions shown in Fig. 36, and in such positions lie within the doorways so as to be entirely out of the way of the doors. The links 239 lie almost wholly within the channels of their respective bars and the frames 240 are substantially parallel with the side of the car with the ends of their arms at the opposite ends of the slotted ribs 242 from the doorways. When the catcher arms are open or in operative position, to which position they are moved through rotation of shaft 197 by shaft 198, as shown by Figs. 2 and 35, they extend divergently forward as shown in Fig. 35, and in moving to such position they swing frame 240 outward and at the same time move it bodily rearward until the slotted ribs 242 arrest further movement in that direction. In the outward movement of the arms and frames, the links 239 are caused to swing pivotally outward on pivots 238 and incidentally exert a pull which results in swinging the auxiliary arms inward until arrested by contact with rib arms 240. When either of the catcher arms is thus arranged it will catch and direct mail bags into the car through the doorway thereof, it being understood that the mail bag or mail bags will be detachably supported along the right-of-way by cranes or equivalent devices, not shown, and in this connection it will be understood that the distance between the arms of each frame 240, will be considerably in excess of the length of the mail bags so that the frame shall not interfere with the passage of the bags between the catcher arms and the car. Reverse movement of the shaft 197 results in refolding the catcher arms to their original position. When the catcher arm is reversed to accommodate reverse movement of the car, the shaft 197 is of course, interlocked with and operated by shaft 205, instead of shaft 198, as will be readily understood.

250 and 250^a indicate levers pivotally engaging the slotted plates 130 and links 131, respectively, of the extensions or shanks 126 and 129 of forks 112 and 122 respectively, and said levers are fulcrumed on the hangers 149 and 149^a respectively and levers 250 are provided at their outer ends with attenuated portions 251, for engagement with channeled hangers 252 depending from the car, such engagement taking place when hangers 149 are adjusted by means of the rock-shafts 154, there being one of these rock shafts in co-operative relation with the mechanism at each side of said car. It will also be noted that one of said hangers 149 is narrower than the other to avoid conflict

with rod 187 (see Fig. 5). Such adjustment of the hangers and consequent locking of said levers from pivotal movement, is also incidental to the disengagement of said levers from the offsetting notches of said slotted plates, as hereinbefore described with reference to levers 147.

Rods 253 pivotally connect the outer ends of levers 250 and 250^a with rack-bars 254 underlying and arranged in suitable guides 255 depending from the car, and said rack bars mesh with cog pinions 256, on the lower ends of short vertical shafts 257, (Figs. 22 and 23), projecting upward into the car. Within and near the floor of the latter, shafts 257 are equipped with cog gears 258 meshing with suitably journaled cog wheels 259, and said cog gears engage parallel rack bars 260 extending transversely of the car, it being noted by reference to Figs. 28 and 29, that there are two sets of these rack bars which abut together at their inner ends, each set being independently movable toward and from the adjacent doorway in the side of the car. Each rack bar 260 is connected by a plate 261 to the horizontal arm of an angle bar 263, and paralleling and secured to said angle bars and plates 261 are angle bars 264. Like the rack bars, there are two sets of angle bars 263 and 264 abutting endwise together, and each set is provided at the outer sides of bars 263 with a pair of track wheels 265. Secured to and projecting beyond the front or outer ends of the angle bars 264 are springs 266 (Figs. 25 and 26) for a purpose hereinafter explained, and secured to each pair of angle bars 263 and 264 and arranged between and projecting beyond vertical arms thereof is a hook 267. The parts 260 to 267 inclusive constitute a pair of tracks which are adapted for travel toward and from the adjacent doorway, only one however, operating at a time.

Arranged upon the bottom of the car and extending longitudinally thereof, is a plurality of inverted channel bars 268, the same being made rigid with the car in any suitable manner, and extending transversely of the car adjacent to and terminating near the doorways thereof and secured upon said channel bars 268 is a pair of I-beam tracks 269, (Fig. 23) the wheels 265 of the trucks resting upon the inner base flanges of the said beams, and incapable of upward movement because of the overlying upper flanges of said beams, as shown clearly in Fig. 23, and secured upon and of slightly greater width than said beams are plates 270, which plates and the upper outer flanges of the beams are provided with openings 271, (Figs. 22 and 27) for a purpose which hereinafter appears.

Secured upon each channel bar 268 is a pair of brackets 272, and connecting each pair of said brackets is an inverted channel

bar 273 carrying a top plate 274 in the same horizontal plane as plates 270, the side margins of said plate terminating above the vertical arms of angle bars 264 as shown clearly in Fig. 23, it being noticed in this connection that the inner side margins of plates 270 terminate above the vertical arms of angle bars 263 so as to provide between plates 270 and plate 274 a pair of longitudinal slots 275. (See Figs. 23 and 27.)

The construction described is duplicated for each pair of opposite doorways though in practice it will be only occasionally that both sets of trucks will be operated.

For operating in conjunction with each pair of abutting trucks, there will be a basket, upon either or both of which the sacks of mail will be stacked for delivery at a station, though it will be infrequent when more than one basket will be employed. Each basket is constructed as follows: 276 is a sheet metal body U-shaped in cross section, as shown most clearly in Fig. 23, and secured to and stiffening the bottom of the basket are U-shaped angle bars 277, and secured to the lower portion thereof are horizontal angle bars 278 which extend transversely of the basket and longitudinally of the car. (See Figs. 22, 24 and 31.) Below the side margins of the basket bars 279 underlie and connect angle bars 278, and each bar 279 is provided at its outer margin and near its ends with a pair of depending flanges 280, which extend downward at the outer sides of plates 270, and carry track wheels 281 resting on the outer base flanges of I-beams 269. (See Figs. 22 and 23.)

Arranged inward of each bar 279 and parallel therewith and secured to bars 278, is a pair of spaced bars 282 and 283, and said bars are provided with parallel flanges 284 and 285 respectively, at their adjacent margins, which flanges are somewhat shorter than the bars and depend vertically through the slots 275 of the trucks and fit at opposite sides of the hooks or catches 267, as shown clearly in Figs. 23 and 24, and said flanges are provided with horizontal slots 286.

287 is a pair of slide blocks each fitting in slots 286 of adjacent flanges 284-285 and provided near their ends with semi-cylindrical upwardly-projecting lugs 288. (See Figs. 24, 33 and 34.) The lugs at corresponding ends of said slide blocks are adapted for engagement with the hook terminals of one set of the catches and the lugs at the other end of said blocks for engagement with the hook terminals of the other set of catches, accordingly as the basket is arranged to discharge sacks of mail through one doorway or the other. In the horizontal plane of angle bars 278 are suitably arranged, spacer blocks 289 arranged between the flanges 284 and 285 for the purpose of spacing the said flanges apart, and also arranged between said

flanges are crank arms 290, of a pair of transverse shafts 291, provided with upwardly-projecting handles 292 for engagement with a notched sector 293 secured externally to one of the side walls of the basket, as shown in Figs. 22 and 32.

Assuming that the basket is to discharge its charge of mail bags, not shown, through the doorway appearing in Fig. 24, the block 287 fitting in slots 286, will be engaged with the catch of the left hand truck and will be secured in such relation by swinging the right hand lever 292 from a vertical position to the position shown in Fig. 22, this action resulting in depressing the crank arm 290 of said lever to the position shown in Fig. 24, and the engagement of the lever with the sector 293 will prevent accidental movement of said crank arm. As the truck is moved outward in a manner hereinafter more particularly explained, it carries the basket with it, the truck movement continuing until its left hand end protrudes slightly through the doorway, as indicated by dotted lines in Fig. 24. At the moment such movement of the truck ends, the rear or endmost rollers 281 of the basket attain a position vertically below openings 271 of the I-beam tracks 269 and the overlying plates 270 and, due to a preponderance of the weight of the basket to the left of the engaged catch, the basket tilts downward to the position shown in Fig. 24, the said rear wheels 281 passing up through said openings 271. The catch constitutes the axis of such tilting movement and the underlying springs 266 cushion it, as shown clearly in Fig. 26. As the movement of the truck is reversed, flanges 284 and 285 which rest upon the outer ends of angle bars 263 of the truck, constitute sliding fulcrums whereby the basket swings back toward a horizontal position, Fig. 25 showing it as the front rollers 281 start to ride upon the front ends of the base portions of the I-beams, the other pair of wheels 281 resting upon the plates 270 upon said I-beams when the basket is in the position shown by Fig. 25 of its reentering travel. In said figure the truck has a distance to travel about equal to one-half the diameter of roller 281, and as such travel is ended the innermost or rear rollers 281 drop down through the openings 271, and upon the outer base flanges of the I-beams. It will also be noticed by reference to Fig. 25, particularly, that the catches 267 have pivotal movement to accommodate the angular positions which the basket assumes, the catches swinging downward to their original positions as the rear rollers drop through the said openings 271. When it is desired to use the basket upon the abutting pair of tracks for delivering mail sacks through the other door, the lever 292 is restored to a vertical position to reelevate its crank arm.

The basket is then run upon the other truck, and in such movement its blocks 287 will engage the inwardly facing hook terminals of the catches of the second truck, the movement of the basket continuing until it is arrested by the left hand ends of the slots 286 engaging said blocks 287. The left hand lever 292 is then manipulated to depress its crank arm 290 for the purpose of preventing disengagement between said blocks and said catches.

Referring now to the construction of the trip which is arranged adjacent to each station which the train will pass without stopping, 294 indicates a tube consisting of two members which extend divergently upward, and said tube is provided at its bottom with a drain hole 295 and is preferably arched above its apex at 296. The tube is arranged adjacent to and outward of one of the track rails 297 and rests upon a pair of the ties 298, and is secured rigidly to the outer end of a pair of stepped chair plates 299 secured to and projecting outwardly from the lower part of the rail, as shown in Fig. 8. Extending through and disposed axially of the upwardly bowed portion 296, is a transverse shaft 300 and depending from said shaft is a crank arm 301, an upwardly projecting crank arm 302 being secured to said shaft inward of the tube and adapted to be struck and operated by one of the V-shaped trip plates 142, of each passing train, in order that such plates shall be forced upward to effect automatic operation of the movable mechanism of the car or the parts of such mechanism that are in proper position to be moved, and in order to avoid injurious shock or jar incident to the contact of a plate 142 with arm 302 of the trip, each tube 294 is closed at its upper end by a plug 303 provided with a tubular guide 304, receiving the stem 305 of a plunger 306, held by a coiled spring 307 against the depending crank arm 301, the opposite ends of the said springs fitting around the tubular guides 304 and bearing against the plugs 303. To clear the trackway of accumulated snow or effect the removal of any other obstruction so that the plate 142 shall not be raised accidentally, a clearing arm 308 is secured to and depends from the car truck in the vertical plane and forward of each plate 142, which arm will not only clear the track of obstructions but will also operate the trip arm 302, which arm will be restored to its initial position by the spring 307 compressed by this movement, so as to be ready to effect the elevation of the plate 142.

Assuming that the basket is in the position shown by full lines, Fig. 22, and that the right hand lever 292 in said figure is adjusted to the position shown, that the doors are closed and the catcher arms are in folded or inoperative position, and that the

pins of the forks 120, 121 and 122 are engaging the slots 98, 99 and 100 respectively of slide bars 87, 88 and 89, the following operations occur as the left hand trip plate 142 is operated by the station trip in its path just before reaching a station: The rod 138 is operated and simultaneously operates lever 136, link 135 and bell crank 133. Through the action of lever 136 (see Fig. 13), the constantly driven shaft 7 is thrown into gear with shaft 17, in order that the rotation of the cam 26 shall result. At the same time the operation of the bell crank 133 imparts endwise movement to slide bar 108, and effects lateral movement of forks 110, 111 and 112 and the consequent unlocking of the same from the keeper 104, and the interlocking of said forks with slide bars 87, 88 and 89, through the entrance of the pins 113 of said forks into the notches 102 of the adjacent slots 98, 99 and 100 of said slide bars (see Fig. 48). As the cam turns in the direction indicated by the arrow, Fig. 14, the portion 33 of the door opening groove imparts sliding movement to bar 87 in the direction indicated by the arrow on said bar in Fig. 14, and hence to the fork 110 and its extension 124. From said fork motion is transmitted to levers 146 and 147 (see Fig. 4) and from said levers opening movement is transmitted from the other mechanism described, to the doors at the left hand side of the car, this opening movement being completed as the pin 94 of said slide bar enters portion 32 of the door opening channel. About the same time the pins 95 and 97 of slide bars 88 and 89, respectively enter portions 39 and 41 of the catcher bar operating channel and truck operating channel. (See Fig. 18.) The continued movement of the cam wheel through the engagement of said last-named pins with said channel portions 37 and 41 imparts similar sliding movement to bars 88 and 89 and through said bars to the forks 111 and 112 respectively. The movement of the fork 111 effects operation of lever 212, which, through rod 211 and the mechanism connected thereto operates shaft 197 and effects the opening or outward movement of the catcher arm at the left hand side of the car. The operation of the fork 112 at the same time effects simultaneous operation of levers 250 and 250^a, which levers through rods 253 and rack bars 260, impart outward movement to both of the trucks adapted for movement toward and from the left hand door openings, though as hereinbefore explained, if lever 250 is interlocked with hanger 252 and the pin at the opposite end of the lever is in the slot of its respective plate 130, only one of the left hand trucks will be operated.

The operation of the truck or trucks as hereinbefore described in detail, will result in projecting their outer ends through the

adjacent uncovered doorway and incidental to this movement the basket or baskets of the truck or trucks will assume a dumping position and thus discharge the mail sacks 5 at the proper point. The results described are produced by the time the pins 95 and 97 respectively, attain the ends of portions 37 and 31 of the catcher arm operating and truck operating channels and as said pin 97 10 passes the reversely bowed portion 40 of the truck operating channel, portion 42 of said channel engages it and begins the withdrawal of the truck and basket, these movements being completed by the time said pin 97 15 again enters the portion 39 of said channel. During the time the catcher arm is moving to open or operative position and the truck is moving outward, pin 94 is traveling in portion 32 of the door opening channel 20 without affecting the position of the open door, and during the return movement of the truck while pin 97 is traveling outward through engagement with portion 42 of the truck-operating channel, pin 95 is in engagement 25 with portion 36 of the catcher arm operating channel and the catcher arm remains in open position. As the pin engaging the truck operating channel re-enters portion 39 of said channel as hereinbefore mentioned, 30 pins 94 and 95 are engaged by portions 34 and 38 respectively, of the door operating and catcher arm operating channels respectively, and as a result the doors and the catcher arm are returned to closed positions. 35 The cam wheel continues its operation until a revolution is completed, when as hereinbefore described it is thrown out of gear with the continuously driven shaft 7, in which position the parts remain until plate 40 192 engages another station trip. Should it be desired to open the doors at the opposite side of the car for the purpose of delivering mail or receiving mail, the mechanism at the left hand side will be rendered 45 inoperative by causing the pins of forks 110, 111 and 112 to engage slots 98, 99 and 100, and the hooks of said forks by automatic engagement with hooks of the keeper 104 will prevent the accidental movement of said 50 forks, it being of course understood that when the mechanism at the right hand side of the car is operated, the pins of the forks 120, 121, and 122 will be engaged with the offsetting notches of the slots 98, 99 and 100, 55 at the corresponding ends of the slide bars 87, 88 and 89 respectively.

A folding shelf 309 is hinged at 310 to the car and is normally held in folded or inoperative position flatly against the car by 60 a catch 311, which catch can be tripped by the clerk in the car, to permit the shelf to swing outwardly until arrested by cables 312 connecting it with the car. This shelf is arranged below the receiving or outer

end of the catcher arm so that if the speed 65 of the car is too slow to carry a sack received from the station crane through the doorway of the car the sack may drop and be caught by the underlying shelf and be taken into the car at the pleasure of the 70 clerk. As the catcher arm is too heavy to be conveniently supported manually, I provide a supporting crane consisting of an overhead track 313, and a hanger 314 preferably adjustable as to length, may be arranged near a doorway at each side of the 75 car. At the upper end of the hanger is a grooved wheel 315 engaging the trackway and at the lower end of the hanger is swiveled a U-shaped clip 316, to embrace one of 80 the bars of the catcher arm, a bolt 317 extending through the ends of the clip so as to hold the latter reliably on said bar. When the clip is engaged with said bar and the catcher mechanism is disengaged from 85 plates 192 and 243, the catcher arm can be revolved vertically until it faces in the opposite direction. The plates 192 and 243 are then transposed with respect to the doorway and secured on the hangers 190 and 191, 90 at the opposite side of the doorway, and plate 243 will be secured on the other set of hangers 245 and 246, as shown in Fig. 2.

For manually effecting a reversal of the rotation of the cam by shifting sleeve 18 95 along shaft 17, a forked lever 318 is pivoted at 319 to frame 9 (see Figs. 4 and 17) and is connected at its forked inner end to collar 21 and at its outer end to a link 320, which link is connected at its opposite end to a 100 transversely-disposed inclined lever 321 (Fig. 2) fulcrumed on a hanger 322 depending from the car. The opposite or upper end of the inclined lever is pivotally connected by a link 323 to a crank arm 324 of 105 a vertical shaft 325 extending up into the car, and provided at its upper end with a crank handle 326 which extends oppositely to crank arm 324. As shown the sleeve 18 is midway between and out of engagement 110 with clutch members 13 and 16, and the crank arm 324 and handle 326 of shaft 325, project outward and inward respectively. Usually the sleeve 18 is at one end or the other of its adjustment to insure rotation of 115 the cam at the proper time, and the mechanism described for shifting the sleeve is so constructed that the handle 326 points in the direction in which the car is traveling, except of course when the car is running 120 backward.

From the above description it will be apparent that I have produced a mail exchange system embodying the features of advantage enumerated as desirable and I wish it to be 125 understood that while I have illustrated and described the preferred embodiment of the invention, I do not desire to be restricted to

the exact details of construction shown and described as obvious modifications will suggest themselves to one skilled in the art.

I claim:

- 5 1. In an automatic mail exchange apparatus, the combination of a railway mail car having a normally stationary shaft, automatic mechanism carried by the car, manually controlled means for throwing said stationary shaft in or out of gear with said mechanism, a driven means carried by the car, means for throwing said driven means in or out of gear with said stationary shaft, and a trackway trip for actuating the last-named means to throw said driven means in gear with said stationary shaft.
- 10 2. In an automatic mail exchange apparatus, the combination of a railway mail car having a normally stationary shaft, automatic mechanism carried by the car, manually controlled means for throwing said stationary shaft in or out of gear with said mechanism, a driven means carried by the car, means for throwing said driven means in or out of gear with said stationary shaft, a trackway trip for actuating the last-named means to throw said driven means in gear with said stationary shaft, and means for automatically throwing said driven means 15 out of gear with the said shaft.

- 20 3. In an automatic mail exchange apparatus, the combination of a railway mail car having a normally stationary shaft, automatic mechanism carried by the car, manually controlled means for throwing said stationary shaft in or out of gear with said mechanism, a driven means carried by the car, means for throwing said driven means in or out of gear with said stationary shaft, a trackway trip for actuating the last-named means to throw said driven means in gear with said stationary shaft, a discharging device actuated by said automatic mechanism to discharge one or more mail bags 25 from the car, and means to throw said driven means out of gear with the said shaft.
- 25 4. In an automatic mail exchange apparatus, the combination of a railway mail car having a normally stationary shaft, automatic mechanism carried by the car, manually controlled means for throwing said stationary shaft in or out of gear with said mechanism, a driven means carried by the car, means for throwing said driven means in or out of gear with said stationary shaft, a trackway trip for actuating the last-named means to throw said driven means in gear with said stationary shaft, a discharging device actuated by said automatic mechanism to discharge one or more mail bags 30 from the car, and means to throw said driven means out of gear with the said shaft.

- 35 5. In an automatic mail exchange apparatus, the combination of a railway mail car having a normally stationary shaft, automatic mechanism carried by the car, manually controlled means for throwing said stationary shaft in or out of gear with said mechanism, a driven means carried by the car, means for throwing said driven means in or out of gear with said stationary shaft, a trackway trip for actuating the last-named means to throw said driven means in gear with said stationary shaft, and a catcher 40 arm carried by the car and adapted to be actuated by said automatic mechanism to swing outward to receive one or more mail bags at a point exterior to the car and deliver such bag or bags within the car while the door is open, and then swing inward to its original position, and means to throw said driven means out of gear with the said shaft after the door is closed and the inward movement of the catcher arm terminates.
- 45 6. In an automatic mail exchange apparatus, the combination with a mail car and driven means carried thereby, of a cam wheel, a slide bar for reciprocation by the cam wheel, connections for transmitting power from the slide bar to a door of the car 45 to open and close such door, a trackway trip and means actuated by the said trip to throw the driven means in gear with the cam wheel.

then swing inward to its original position, 65 and means to throw said driven means out of gear with the said shaft.

5. In an automatic mail exchange apparatus, the combination of a railway mail car having a normally stationary shaft, automatic mechanism carried by the car, manually controlled means for throwing said stationary shaft in or out of gear with said mechanism, a driven means carried by the car, means for throwing said driven means in or out of gear with said stationary shaft, a trackway trip for actuating the last-named means to throw said driven means in gear with said stationary shaft, means actuated by the said automatic mechanism for opening and closing a door of the car, a discharging device actuated by said automatic means to discharge one or more mail bags from the car while the door is open, and means to throw said driven means out of gear with said shaft after the door has been reclosed.

6. In an automatic mail exchange apparatus, the combination of a railway mail car having a normally stationary shaft, automatic mechanism carried by the car, manually controlled means for throwing said stationary shaft in or out of gear with said mechanism, a driven means carried by the car, means for throwing said driven means in or out of gear with said stationary shaft, a trackway trip for actuating the last-named means to throw said driven means in gear with said stationary shaft, a trackway trip for actuating the last-named means to throw said driven means in gear with said stationary shaft, means actuated by the said automatic mechanism for opening and closing a door of the car, and a catcher arm carried by the car and adapted to be actuated by said automatic mechanism to swing outward to receive one or more mail bags at a point exterior to the car and deliver such bag or bags within the car while the door is open, and then swing inward to its original position, and means to throw said driven means out of gear with the said shaft after the door is closed and the inward movement of the catcher arm terminates.

7. In an automatic mail exchange apparatus, the combination with a mail car and driven means carried thereby, of a cam wheel, a slide bar for reciprocation by the cam wheel, connections for transmitting power from the slide bar to a door of the car 120 to open and close such door, a trackway trip and means actuated by the said trip to throw the driven means in gear with the cam wheel.

8. In an automatic mail exchange apparatus, the combination with a mail car and driven means carried thereby, of a cam member, a member actuated by the cam member, connections for transmitting motion from the

cam actuated member to a door of the car to open and close such door, a trackway trip, means actuated by the said trip to throw the driven means in gear with the cam member, and means for automatically throwing the cam member and driven means out of gear as the former completes a cycle of movement.

9. In an automatic mail exchange apparatus, the combination with a mail car and driven means carried thereby, of a cam member, a member actuated by the cam member, connections for transmitting motion from the cam actuated member to a door of the car to open and close such door, a trackway trip, means actuated by the said trip to throw the driven means in gear with the cam member, and manually controlled means for throwing the cam member out of gear with the driven means or for effecting reverse or backward movement of the cam member.

10. In an automatic mail exchange apparatus, the combination with a mail car and driven means carried thereby, of a cam member, a member actuated by the cam member, a catcher arm hingedly connected to the car, a trackway trip, means actuated by the said trip to throw the driven means in gear with the cam member, and connections for transmitting motion from the cam actuated member to the catcher arm to swing the same outwardly to operative and inwardly to inoperative position.

11. In an automatic mail exchange apparatus, the combination with a mail car and driven means carried thereby, of a cam member, a member actuated by the cam member, a catcher arm hingedly connected to the car, a trackway trip, means actuated by the said trip to throw the driven means in gear with the cam member, connections for transmitting motion from the cam actuated member to the catcher arm to swing the same outwardly to operative and inwardly to inoperative position, and means for automatically throwing the cam member and driven means out of gear as the former completes a cycle of movement.

12. In an automatic mail exchange apparatus, the combination with a mail car and driven means carried thereby, of a cam member, a member actuated by the cam member, a catcher arm hingedly connected to the car, a trackway trip, means actuated by the said trip to throw the driven means in gear with the cam member, connections for transmitting motion from the cam actuated member to the catcher arm to swing the same outwardly to operative and inwardly to inoperative position, and manually controlled means for throwing the cam member out of gear with the driven means or for effecting reverse or backward movement of the cam member.

13. In an automatic mail exchange appa-

ratus, the combination with a mail car and driven means carried thereby, said car having a doorway and a door therefor, of a cam member, members independently actuated by the said cam member, a trackway trip, means actuated by the said trip to throw the said driven means in gear with the cam member, a catcher arm hingedly attached to the car, connections for transmitting motion from one of said cam actuated members to the door to open and close the same, and connections for transmitting motion from the other of said cam actuated members to the catcher arm to swing the same outward from the car to operative position, to receive and deliver one or more mail bags through the doorway into the car, and then back to inoperative position.

14. In an automatic mail exchange apparatus, the combination with a mail car and driven means carried thereby, said car having a doorway and a door therefor, of a cam member, members independently actuated by the said member, a trackway trip, means actuated by the said trip to throw the said driven means in gear with the cam member, a catcher arm hingedly attached to the car, connections for transmitting motion from one of the said cam actuated members to the door to open and close the same, connections for transmitting motion from the other of said cam actuated members to the catcher arm to swing the same outward from the car to operative position, to receive and deliver one or more mail bags through the doorway into the car, and then back to inoperative position.

15. In an automatic mail exchange apparatus, the combination with a mail car and driven means carried thereby, said car having a doorway and a door therefor, of a cam member, members independently actuated by the said cam member, a trackway trip, means actuated by the said trip to throw the said driven means in gear with the cam member, a catcher arm hingedly attached to the car, connections for transmitting motion from one of the said cam actuated members to the door to open and close the same, connections for transmitting motion from the other of said cam actuated members to the catcher arm to swing the same outwardly from the car to operative position, to receive and deliver one or more mail bags through the doorway into the car, and then back to inoperative position, and manually controlled means for throwing the cam member out of gear with the driven means or for effecting reverse or backward movement of the cam member.

16. In an automatic mail exchange appa-

10 driven means carried thereby, of a cam member, a member actuated by the cam member, a trackway trip, means actuated by said trip to throw the driven means in gear with the cam member, a mail bag discharging device carried by the car, and connections for transmitting motion from said cam actuated member to said device to actuate the same to effect discharge of its contents and then return it to its inoperative position.

15 17. In an automatic mail exchange apparatus, the combination with a mail car and driven means carried thereby, of a cam member, a member actuated by the cam member, a trackway trip, means actuated by said trip to throw the driven means in gear with the cam member, a mail bag discharging device carried by the car, connections for transmitting motion from said cam actuated member to said device to actuate the same to effect the discharge of its contents and then return it to its inoperative position, and means for automatically throwing the cam member and driven means 25 out of gear as the former completes a cycle of movement.

30 18. In an automatic mail exchange apparatus, the combination with a mail car and driven means carried thereby, of a cam member, a member actuated by the cam member, a trackway trip, means actuated by said trip to throw the driven means in gear with the cam member, a mail bag discharging device carried by the car, connections for transmitting motion from the said cam actuated member to said device to cause the same to effect the discharge of its contents and then return it to its inoperative position, and manually controlled means for throwing the 35 cam member out of gear with the driven means or for effecting reverse or backward movement of the cam member.

40 19. In an automatic mail exchange apparatus, the combination with a mail car and driven means carried thereby, said car having a doorway and a door therefor, of a cam member, members actuated by said cam member, a trackway trip, means actuated by said trip to throw the driven means in gear with the cam member, a mail bag discharging device within the car and adapted to hold one or more mail bags, connections between one of said cam actuated members and said door to open and close the same, and 45 connections between the other of said cam actuated members and said discharging device to actuate the latter to move outward through the doorway and discharge its contents and return within the car during the 50 interim between the opening and closing movements of the door.

55 20. In an automatic mail exchange apparatus, the combination with a mail car and driven means carried thereby, a slide bar, a normally inactive rotatable means for oper-

ating the slide bar, a trackway trip, means actuated by the trackway trip to cause said driven means to operate said normally inactive rotatable means, and connections between said slide bar and a door of the car to open and close said door. 70

21. In an automatic mail exchange apparatus, the combination with a mail car and driven means carried thereby, a slide bar, a normally inactive rotatable means for operating the slide bar, a trackway trip, means actuated by the trackway trip to cause said driven means to operate said normally inactive rotatable means, a catcher arm hingedly supported on the car, and connections between said slide bar and said catcher arm to cause the latter to swing outward from the car and back to its original position. 75

22. In an automatic mail exchange apparatus, the combination with a mail car and driven means carried thereby, said car having an opening therein, a slide bar, a normally inactive rotatable means for operating the slide bar, a trackway trip, means actuated by the trackway trip to cause said driven means to operate said normally inactive rotatable means, a mail bag discharging device within the car, and connections between said slide bar and said discharging device for causing the latter to move outward through said opening and return to its original position. 80

23. In an automatic mail exchange apparatus, the combination with a mail car and driven means carried thereby, normally inactive mechanism carried by the car, a slide bar to be reciprocated by such mechanism, a trackway trip, means actuated by the trackway trip to throw the driven mechanism in gear with the normally inactive mechanism, and means for throwing said driven mechanism and normally inactive mechanism out of gear after moving said slide bar endwise in one direction and returning it to its original position. 85

24. In an automatic mail exchange apparatus, the combination with a mail car and driven means carried thereby, said car having a doorway and a door therefor, normally inactive mechanism carried by the car, a slide bar to be reciprocated by such mechanism, a trackway trip, means actuated by the trackway trip to throw the driven mechanism in gear with the normally inactive mechanism, means for throwing said driven mechanism and normally inactive mechanism out of gear after moving said slide bar endwise in one direction and returning it to its original position, and means whereby said movements of the slide bar shall respectively effect the opening and closing said door. 100

25. In an automatic mail exchange apparatus, the combination with a mail car and driven means carried thereby, normally in- 105

- active mechanism carried by the car, a slide bar to be reciprocated by such mechanism, a trackway trip, means actuated by the trackway trip to throw the driven mechanism in gear with the normally inactive mechanism, means for throwing said driven mechanism and normally inactive mechanism out of gear after moving said slide bar endwise in one direction and returning it to its original position, a catcher arm hinged to the side of the car, and means whereby said movements of the slide bar shall respectively swing the catcher arm outward and inward.
26. In automatic mail exchange apparatus, the combination with a mail car and driven means carried thereby, normally inactive mechanism carried by the car, a slide bar to be reciprocated by such mechanism, a trackway trip, means actuated by the trackway trip to throw the driven mechanism in gear with the normally inactive mechanism, means for throwing said driven mechanism and normally inactive mechanism out of gear after moving said slide bar endwise in one direction and returning it to its original position, a discharging device within the car, and means whereby said movements actuate the discharging device to effect the discharge of mail bags from the car, and return said device to its initial position.
27. In automatic mail exchange apparatus, the combination with a mail car and driven means carried thereby, said car having a doorway and a door therefor, normally inactive mechanism carried by the car, a pair of slide bars to be reciprocated by said mechanism, a trackway trip, means actuated by the said trip to throw the driven means in gear with the normally inactive mechanism to effect endwise movement of said slide bars in one direction and return them to their original positions, means actuated by one of said slide bars in said movements to open and close said door, a hingedly supported catcher arm, and means actuated by the other slide bar in said movements to swing the catcher arm outward and return it to its original position.
28. In automatic mail exchange apparatus, the combination with a mail car and driven means carried thereby, said car having a doorway and a door therefor, normally inactive mechanism carried by the car, a pair of slide bars to be reciprocated by said mechanism, a trackway trip, means actuated by the said trip to throw the driven means in gear with the normally inactive mechanism to effect endwise movement of said slide bars in one direction and return them to their original positions, means actuated by one of said slide bars in said movements to open and close said door, a mail bag discharging device within the car, and means actuated by the other slide bar to project the

discharging device through said doorway and return it to its original position while the door is open.

29. In an automatic mail exchange apparatus, the combination with a railway mail car and driven means carried thereby, said car having a doorway and a door therefor, of a cam member, means locking the cam wheel against accidental movement, a member actuated by the cam member, connections for transmitting motion from said cam actuated member to said door to open and close the same, a trackway trip, means actuated by the trackway trip for unlocking the cam member and throwing the driven means in gear therewith, and means actuated as the cam member completes a cycle of movement to throw the cam member out of gear with the driven means and into operative relation with the locking means. 85

30. In an automatic mail exchange apparatus, the combination with a railway mail car and driven means carried thereby, of a cam member, means locking the cam member against accidental movement, a member actuated by the cam member, a catcher arm hingedly carried by the car, connections for transmitting motion from said cam actuated member to the catcher arm to swing the same outwardly from and back toward the car, a trackway trip, means actuated by the trackway trip for unlocking the cam member and throwing the driven means in gear therewith, and means, actuated as the cam member completes a cycle of movement, to throw the cam member out of gear with the driven means and into operative relation with the locking means. 95

31. In an automatic mail exchange apparatus, the combination with a railway mail car and driven means carried thereby, of a cam member, means locking the said cam member against accidental movement, a member actuated by the cam member, a mail bag discharging device on the car, connections for transmitting motion from said cam actuated member to the discharging device to actuate the same and then return it to its original position, a trackway trip, means actuated by the trackway trip for unlocking the cam member and throwing the driven means into gear therewith, and means, actuated as the cam member completes a cycle of movement, to throw the same out of gear with the driven means and into operative relation with the locking means. 115

32. In an automatic mail exchange apparatus, the combination with a railway mail car and driven means carried thereby, said car having a doorway and a door therefor, of a cam member, means locking the cam member against accidental movement, members actuated by the cam member, connections for transmitting motion from one of 125

5 said cam actuated members to said door to open and close the same, a discharging device within the car, connections between the other said cam actuated members and said discharging device to project the latter through said doorway and return it to its original position while the door is open, a trackway trip, means actuated by the trackway trip for unlocking the cam member and 10 throwing the driven means into gear therewith, and means actuated as the cam member completes a cycle of movement, to throw the cam member out of gear with the driven means and into operative relation with the locking means.

33. In an automatic mail exchange apparatus, the combination with a railway mail car and driven means carried thereby, said car having a doorway and a door therefor, 20 of a cam member, means locking the cam member against accidental movement, members actuated by the cam member, connections for transmitting motion from one of said cam actuated members to said door to open and close the same, a hingedly supported catcher arm, connections between the other of said cam actuated members, and said catcher arm to swing the same outward from and back toward the car, a trackway 25 trip, means actuated by the trackway trip for unlocking the cam member and throwing the driven means into gear therewith, and means actuated by the cam member as it completes a cycle of movement, to throw the same out of gear with the driven means and into operative relation with the locking means.

34. The combination with a mail car having a side door opening, of a device for delivering mail bags to the car through said opening, comprising a catcher arm hinged at its rear end to the car, an arm pivoted to the first-named arm near the hinged end of the latter, a U-shaped frame pivoted to the catcher arm forward of its pivotal point of connection with the said second arm and having a sliding connection at its front end with the side of the car, and a link pivotally connecting the rear end of said frame with the rear end of said second arm.

35. The combination with a mail car having a side door opening, of a device for delivering mail bags to the car through said opening, comprising a catcher arm hinged at its rear end to the car, an arm pivoted to the first-named arm near the hinged end of the latter, a U-shaped frame pivoted to the catcher arm forward of its pivotal point of connection with the said second arm and 50 having a sliding connection at its front end with the side of the car, a link pivotally connecting the rear end of said frame with the rear end of said second arm, means for engagement with said second arm to limit 60 opening movement of the catcher arm, and

means for imparting outward or inward swinging movement to the catcher arm and through said frame and link, inward or outward movement respectively, to said second arm.

70

36. In a railway mail exchange apparatus, a trackway consisting of a pair of parallel I-beams having transversely alined openings in their upper outer flanges, and a truck arranged between said I-beams and provided with wheels on the lower inner flanges of the beams, springs projecting beyond the advanced end of the truck, pivoted catches at the corresponding end of the truck, and a pair of rack-bars in combination with intermeshing gear wheels engaging said rack-bars, and means for rotating one of said wheels to impart longitudinal movement in one direction or the other to the truck.

75

80

37. In a railway mail exchange apparatus, 85 a trackway consisting of a pair of parallel I-beams having transversely alined openings in their upper outer flanges, and a truck arranged between said I-beams and provided with wheels on the lower inner flanges 90 of the beams, springs projecting beyond the advanced end of the truck, pivoted catches at the corresponding end of the truck, and a pair of rack-bars in combination with intermeshing gear wheels engaging 95 said rack-bars, and means for rotating one of said wheels to impart longitudinal movement in one direction or the other to the truck, and a basket above the truck and trackway, provided with depending hangers 100 at the outer sides of the trackway, wheels carried by said hangers and resting on the lower outer flanges of the trackway, depending longitudinally-extending slotted flanges receiving between them said catches, 105 slideable blocks mounted between said flanges and in the slots thereof and hingedly engaged by said catches, and means for holding the catches and blocks interlocked together at a point rearward of the center of 110 gravity of the basket.

105

38. In a railway mail exchange apparatus, a trackway consisting of a pair of parallel I-beams, having transversely alined openings in their upper outer flanges, and a truck arranged between said I-beams and provided with wheels on the lower inner flanges of the beams, springs projecting beyond the advanced end of the truck, pivoted catches at the corresponding end of 120 the truck, and a pair of rack-bars in combination with intermeshing gear wheels engaging said rack-bars, and means for rotating one of said wheels to impart longitudinal movement in one direction or the other 125 to the truck, and a basket above the truck and trackway, provided with depending hangers at the outer sides of the trackway, wheels carried by said hangers and resting on the lower outer flanges of the trackway, 130

depending longitudinally-extending slotted flanges receiving between them said catches, 5 slideable blocks mounted between said flanges and in the slots thereof and hingedly engaged by said catches, a transverse shaft carried by and below the basket and provided with a crank to hold the blocks and catches in engagement, and a notched sector at one end of the basket for engagement by said lever.

39. In railway mail exchange apparatus, a substantially U-shaped basket, carrying wheels for and below the corners of the same, parallel longitudinally-extending slotted flanges depending from the basket, 15 slideable blocks mounted in said flanges, a pair of transverse shafts carried by and below the basket, oppositely projecting cranks secured to said shafts between said flanges, 20 upwardly-projecting levers secured to said shafts at one side of the basket, and a notched sector secured to the corresponding side of the basket and adapted for engagement by said levers to hold the same in 25 vertical and inoperative or inclined and operative positions.

40. In automatic mail exchange apparatus, the combination with a mail car, of a trackway terminating at one end adjacent 30 to the doorway of the car, a truck for travel on said trackway toward and from the doorway, a basket carried by and pivotally connected at a point to the rear of its center of gravity to the truck and adapted when projected out of the doorway a certain distance by movement in the same direction of the truck, to tilt downwardly and outwardly until arrested by the advanced end of the truck and adapted as the movement of the 40 truck is reversed to encounter the door sill and be retilted thereby.

41. In automatic mail exchange apparatus, the combination with a mail car, containing a trackway terminating at one end 45 adjacent to a side door of the car and provided with openings, of a truck for travel on said trackway, means for moving the truck toward and from said doorway, a basket movable with the truck and provided 50 with front and rear wheels to run on said trackway until its front end is projected through the doorway and its front wheels have passed off and beyond the front end of the trackway and its rear wheels are opposite said openings, said basket being pivoted at a point rearward of its center of gravity to the truck to tilt and swing downward through the doorway and cause said rear wheels to swing upwardly through said 55 openings, the basket being adapted as the movement of the truck is reversed to engage and be tilted back by the door sill until the front wheels ride upon the trackway and the rear wheels drop by force of gravity 60 through said openings and then move with 65

the truck until the rear wheels are withdrawn from alignment with said openings.

42. In automatic mail exchange apparatus, the combination with a mail car, containing a trackway terminating at one end 70 adjacent to a side door of the car and provided with openings, of a truck for travel on said trackway, means for moving the truck toward and from said doorway, a basket movable with the truck and provided 75 with front and rear wheels to run on said trackway until its front end is projected through the doorway and its front wheels have passed off and beyond the front end of the trackway and its rear wheels are opposite said openings, said basket being pivoted at a point rearward of its center of gravity to the truck to tilt and swing downward through the doorway and cause said rear wheels to swing upwardly through said 80 openings, the basket being adapted as the movement of the truck is reversed to engage and be tilted back by the door sill until the front wheels ride upon the trackway and the rear wheels drop by force of gravity 85 through said openings and then move with the truck until the rear wheels are withdrawn from alignment with said openings, and means to cushion the downward tilting movement of the basket. 90

43. In automatic mail exchange apparatus, the combination with a mail car of a truck therein for movement toward and from a side door opening thereof, a basket movable with and pivoted at a point rearward of its center of gravity to the truck and adapted as the latter ends its movement toward the doorway, to tilt downwardly through the latter and as the reverse movement of the truck occurs to encounter 100 the door sill and be tilted back to its original position.

44. In automatic mail exchange apparatus, the combination with a mail car, of a pair of transversely aligned trucks therein, 110 each being movable toward and from one of a pair of opposite openings in the sides of the car, and each provided at its front or outer end with a pivoted inwardly-facing hook, and a basket adjustable to occupy a 115 superposed relation to either of said trucks and provided with a longitudinal slot extending transversely of the car, a pivot block adjustable in said slot and adapted in operation to occupy a position at one end or the 120 other thereof and be pivotally engaged at a point rearward of the center of gravity of the basket by the hook of the underlying truck, and means carried by the basket for guarding against accidental disengagement 125 between its pivot block and the pivot hook of said underlying truck.

45. In automatic mail exchange apparatus, the combination with a mail car, of a pair of transversely aligned trucks therein, 130

each being movable toward and from one of a pair of opposite openings in the sides of the car, and each provided at its front or outer end with a pivoted inwardly-facing hook, and a basket adjustable to occupy a superposed relation to either of said trucks and provided with a longitudinal slot extending transversely of the car, a pivot block adjustable in said slot and adapted in operation to occupy a position at one end or the other thereof and be pivotally engaged at a point rearward of the center of gravity of the basket by the hook of the underlying truck, a lever carried by the basket, a crank arm movable with the lever to engage the opposite side of the hook to prevent disengagement therefrom of said block, and means to hold the lever with said arm in engagement with said hook.

46. In railway mail exchange apparatus, the combination with a mail car, of a driven shaft, a rotatable cam wheel, a ring carried thereby and provided with an opening, a pivoted catch carried by said ring and provided with a lug depending through the opening of the ring, a clutch member rotatable with and slidable on said driven shaft, an engaging yoke slidable with said clutch member and interlocked with said ring to hold the same stationary, a stationary shaft geared to turn the cam wheel, a clutch member on said shaft, a disengaging yoke held advanced by the lug of said catch, a slidable rod movable with said engaging yoke, yielding means held compressed by said disengaging yoke and holding the same pressed against said lug, a trackway trip, means actuated by the trackway trip to trip said catch and effect rearward movement of said rod, the disengaging yoke and the engaging yoke to unlock the same from said ring and interlock the slidable clutch with the clutch of the stationary shaft, the lug of said catch being adapted as the cam wheel completes a revolution to reengage and return the disengaging yoke to its original position and through such return movement of said disengaging yoke effect the disengagement of the slidable clutch member from the other clutch member and the interlocking of the engaging yoke with said ring to arrest the cam wheel as the revolution therewith is completed and also simultaneously effect the return of the catch tripping means to its original position.

47. A catcher arm for railway mail cars, comprising a plurality of channel bars pivoted at one end to the car and provided at such end with openings and outward of said openings with external channels, a horizontally arranged U-shaped frame having a pin and slot connection at one end with the car and fitting around said catcher arm, arms projecting from the bridge or closed end of said frame and pivoted at their opposite

ends to and within the channels of said bars, supplemental bars projecting into the slots of and pivoted to said bars, and links pivoted at corresponding ends to said supplemental bars and at their other ends to the said arms of the U-shaped frame and adapted at times to lie with the arms of the U-shaped frame snugly in the channels of the first-named bars.

48. The combination with a mail car, having a side door opening, a plate detachably secured to the car at one side of the opening, a plate detachably secured to the car at the opposite side of the opening, a catcher arm carried by one of said plates and projecting toward the other, a brace pivotally connected to the other plate and said catcher arm, and a crane to support said parts when it is desired to dispose them in operative position to accommodate reverse travel of the car.

49. The combination with a mail car, having a side door, opening, a plate detachably secured to the car at one side of the opening, a plate detachably secured to the car at the opposite side of the opening, a catcher arm carried by one of said plates and projecting toward the other, a brace pivotally connected to the other plate and said catcher arm, and a crane carried by the car and provided with a swiveled clip for engagement with the catcher arm to lift, support and permit the same to be turned a half revolution in a plane substantially parallel with the side of the car.

50. In an automatic mail exchange apparatus, the combination of a car having an opening therein, a rotatable cam, a member adapted to be actuated by said cam in each revolution thereof, a catcher arm hingedly mounted on the car at the rear side of an opening, said means for transmitting motion from said member to said catcher arm to swing the same outwardly to operative and inwardly to inoperative position.

51. In an automatic mail exchange apparatus, the combination of a car having an opening therein, a rotatable cam, a member adapted to be actuated by said cam in each revolution thereof, a catcher arm hingedly mounted on the car at the rear side of an opening, means for transmitting motion from said member to said catcher arm to swing the same outwardly to operative and inwardly to inoperative position, and means for preventing the transmission of motion from said bar to the said catcher arm.

52. In an automatic mail exchange apparatus, the combination of a car, a rotatable cam, a slide bar for reciprocation by said cam in each revolution thereof and provided with a longitudinal slot having an offset, a catcher arm hinged to the car, a movable device connected to swing said catcher arm to operative and inoperative position,

and a pin secured to said device and adapted to engage either the body portion or the offset portion of the slot of said bar.

53. In an automatic mail exchange apparatus, the combination of a car, a rotatable cam, a slide bar for reciprocation by said cam in each revolution thereof and provided with a longitudinal slot having an offset, a catcher arm hinged to the car, a movable device connected to swing said catcher arm to operative and inoperative position, a pin secured to said device and adapted to engage either the body portion of the offset portion of the slot of said bar, and means whereby said device may be held against movement when the pin thereof engages the body portion of the slot of said bar.

54. In an automatic mail exchange apparatus, the combination of a car having a door, a rotatable cam, a member adapted to be actuated by said cam in each revolution thereof, movable means for discharging mail from the car, and means for transmitting motion from said member to said mail discharging means to operate and then return the latter to normal position.

55. In an automatic mail exchange apparatus, the combination of a car having a

door, a rotatable cam, a member adapted to be actuated by said cam in each revolution thereof, movable means for discharging mail from the car, means for transmitting motion from said member to said mail discharging means to operate and then return the latter to normal position, and means for preventing the transmission of motion from the said member to the said mail discharging means.

56. In an automatic mail exchange apparatus, the combination of a car, a rotatable cam, a slide bar for reciprocation by said cam in each revolution thereof and provided with a slot having an offset portion, a movable mail discharging device within the car, a device for imparting back and forth movement to said mail-discharging device and provided with a pin, and means for causing said pin to engage the body portion or offsetting portion of said slot.

In testimony whereof I affix my signature, in the presence of two witnesses.

ALBERT HUPP.
